WATCH

Paul Arbey, Geneva, Switzerland, assignor to the
firm Rolex Watch Co. Ltd., Geneva, Switzerland

Application June 7, 1940, Serial No. 339,396
In Switzerland June 12, 1939

2 Claims. (Cl. 58—126)

The present invention relates to a watch or wrist watch and has reference more particularly to improvements in the construction and arrangement of dials used in such watches.

- 5 It is an object of the invention to provide two dial plates disposed one above the other in overlying relation to the movement, the upper of said plates having a suitable aperture through which the lower dial plate may be viewed.
- 10 With the object in view, the invention resides in those novel features of construction, combination and arrangements of parts which will be hereinafter first fully described, and then be specifically pointed out in the appended claims, reference being had to the accompanying drawing, illustrating a preferred and practical but obviously not the only embodiment of the invention.
- 15 Figures 1 and 3 are, respectively, a front and rear face view of a wrist watch embodying the invention; Figure 2 is a sectional view taken substantially on line 2—2 of Figure 1.

The improved watch shown includes a casing formed of an annular main body 1 the upper 25 part of which affords a bezel 1a for the glass 3, while the lower part thereof is internally threaded as at 1b to receive an externally threaded back or bottom 2 which can be screwed into said main body. This case is shown bearing a cylindrical space 4 in which a similarly shaped movement 5 fits. A first or lower dial plate 6 is fixed to the movement 5, and the latter is also provided with the usual time indicating means or hands 7.

The aperture of the bezel 1a has, as seen from 35 the top, a rectangular shape, and its four corners extend beyond the circular circumference of the space 4 so as to form seats 8 disposed on about the same level as the lower dial plate 6 and adapted to support a second or upper dial plate 40 9 conforming to said aperture and disposed to overlie the lower dial 6 in close relationship therewith. The said upper dial plate presents a central aperture 10 preferably of rectangular form through which the lower dial may be viewed.

45 Adjacent the aperture 10 of the upper dial is a time graduation 11 as best seen in Figure 1, and the time indicating means or hands 7 are so arranged that the largest hand indicating the seconds is disposed above the upper dial 9, while the

smaller hands indicating the hours and minutes are disposed to turn within the central aperture 10 of said upper dial. Obviously, the minute hand could also be disposed similarly to the second hand to turn above the upper dial 9.

5 The described watch is assembled in the following way:

First, the upper dial 9 is introduced with a press fit into the bezel 1a; however, if desired, the said upper dial may be fitted loosely into 10 said bezel and held therein by means of any convenient tool; then the glass is fixed to the bezel 1a. Afterwards, the movement having fixed thereon the lower dial 6 and the hands 7 is introduced from the bottom of the case into the space 15 4 of the annular main body 1, the second hand, and eventually the minute hand, having first been directed towards a corner of the aperture 10 of the dial 9. Finally, the back 2 is screwed into the said main body.

20 It should be understood that it is not intended to limit the invention to the exact details of construction herein shown and described, for various modifications within the scope of the claims may occur to persons skilled in the art.

25 What is claimed and desired to be secured by Letters Patent is:

1. Watch having in combination, a casing bearing a cylindrical space, a movement removably received in said space, a first or lower dial 30 carried by said movement, a bezel on said casing, said bezel having an aperture extending at least in part beyond the circumference of said space so as to form seats disposed on about the same level as said lower dial, a second or upper dial 35 conforming to said aperture and resting on said seats of the bezel in overlying relation to the lower dial, said upper dial having a central aperture through which said lower dial may be viewed, a glass fixed to said bezel, and time indicating 40 means on said movement.

2. Watch as claimed in claim 1, said time indicating means comprising at least two hands of large and small size, respectively, the large hand being disposed above the upper dial, and the 45 small hand being disposed within the central aperture of said dial.

PAUL ARBEY.
